(57) **CLAIM**

(21) Appl. No.: **29/096,096**

We claim the ornamental design for an indirect ophthalmoscopy lens retaining ring, as shown and described.

(22) Filed: **Nov. 4, 1998**

DESCRIPTION

(51) LOC (7) Cl. **24-01**

FIG. 1 is a side elevational view of an indirect ophthalmoscopy lens retaining ring, showing our new design;
FIG. 2 is a cross-sectional view taken along line 2—2 of FIG. 1;

(52) U.S. Cl. **D24/172**

FIG. 3 is an end elevational view taken from the right of FIG. 1; and,

(58) Field of Search D24/172; 351/205,
351/219, 223, 214, 245

FIG. 4 is an end elevational view taken from the left of FIG. 1.
